UNITED STATES PATENT OFFICE.

ABRAHAM STOLLER, OF NEW YORK, N. Y.

SAFETY APPLIANCE FOR ELEVATORS.

Application filed June 20, 1924. Serial No. 721,151.

The object of my invention is to supplement elevator safety mechanism of the automatic type well known in the art by auxiliary appliances within the control of a person in the car, so as to preclude the possibility of accident in case of the failure, in whole or in part, of said usual automatic means, under which conditions, as heretofore prevalent, the elevator would not only be endangered but rendered inoperative in so far as the occupants of the car were concerned.

Hence I provide suitable means adapted to be manually controlled within the car, and auxiliary to the usual extraneous automatic safety means, whereby, in case of emergency, the car may be effectually controlled through the medium of an auxiliary brake mechanism adapted to act in conjunction with the governor rope of the ordinary safety mechanism, and whereas also the power may be shut off or applied according to circumstances and requirements, all as hereinafter fully set forth,—the invention consisting essentially in the specific combination and arrangement of devices and appurtenances described and claimed whereby these and other advantageous results are attained, and distinctive features being the control of an auxiliary brake device but duplex emergency means, one electrical and the other mechanical, whereby the setting of the auxiliary brake also cuts out the motor, which is subject to control and reinstatement by an independent electrical circuit, so that practically, to all intents and purposes, the car is self-contained in this respect, and may be safe-guarded and manipulated independent of the usual automatic governor-controlled mechanism.

In the accompanying drawings I illustrate more or less diagrammatically the practical embodiment of the essential features of my invention, although I do not wish to restrict myself to the identical form and construction of device, parts and appurtenances shown by way of exemplification, since modifications may be made in minor details, and equivalent mechanical expedients resorted to with like results, and without departing from the spirit and intent of my invention in this respect.

With this understanding:—

Fig. 1, represents an elevator car and well known automatic governor-control mechanism used in conjunction therewith, the

car being also provided with my auxiliary safety control means;

Fig. 2, is a view of the underside of the car, showing one of the usual guard rail 60 brakes;

Fig. 3, is a view of the casing of the auxiliary brake, broken away in part to show said brake device in detail, in elevation;

Fig. 4, is a horizontal sectional elevation 65 taken upon plane of line 4—4 Fig. 3.

The car C, is supported and raised and lowered normally by any suitable or well known means, not shown, the same forming no part of my invention. R, R, are the usual flange guide rails; G, the usual governor rope connected above with the customary governor-control mechanism G¹, and below with the usual weighted sheave G². g, is the tension rope connecting the governor 70 rope G, with the usual guide rail blocks g', g', underneath the car in a manner well known in the prior state of the art, as illustrated in Fig. 2.

B, is my auxiliary brake arranged to engage, upon occasion, with a strand of the governor rope G, which extends through the casing K, in which the brake B, is pivotally mounted, said casing K, being formed with a semi-circular bearing groove k, for the accommodation of the governor rope G, as will be understood by reference more particularly to Figs. 3 and 4, of the drawings. The brake B, is held normally from contact with the rope G, by a retractile spring k' as shown particularly in Fig. 3, of the drawings; and the brake-actuating cam or eccentric E, is held normally out of contact with the brake B, by a spring e, interposed between a shoulder e' on the eccentric rod e², and a fixed part 95 k², of the casing K, as indicated in Fig. 3.

The eccentric rod e², extends through a solenoid S, said rod being provided with or formed to function as the core of said solenoid S, and the extension of said rod e², below the solenoid S, being formed with a cam protuberance e³, for contractual engagement with a switch a, adapted to open the electrical circuit a', a', when the brake-actuating rod e², is depressed,—said electrical circuit a', a', controlling the motor power circuit as indicated diagrammatically in the lower part of Fig. 1, of the drawings.

The auxiliary brake B, may also be actuated through the medium of a handle e⁴, connected by a flexible cord or equivalent e⁵, with the aforesaid rod e², as indicated in

Fig. 1, of the drawings, so that alternative means are thus provided for applying the emergency brake B, and opening the power circuit.

5 In order to positively effect the re-closing of the motor power circuit upon the release of the auxiliary brake B, I provide an auxiliary electrical circuit a^2 , a^2 , closable upon occasion by a press button a^3 , whereby the 10 parts and connections may be restored to normal relationship.

In use in emergency the auxiliary brake B, may be applied by either pressing the button s' , thereby closing the circuit s , s , 15 of the solenoid S, and actuating the rod e^2 , or the same result may be attained by means of the handle e^4 , should the solenoid S, fail to function for any reason.

20 Heretofore in case of accident or impairment of the governor-control mechanism, the occupants of the car have been comparatively helpless, having to rely on extraneous assistance, whereas by my invention the car can be manipulated effectually from 25 within in case of necessity. Furthermore, my safety mechanism and appurtenances may be tested out from time to time without injury, and without the necessity for dis-

mantling of the car or parts involved,—a result not heretofore attained in safety appliances for elevators of the character designated.

What I claim as my invention and desire to secure by Letters Patent, is:—

1. In combination with an elevator of the character designated, an auxiliary brake positioned on the car, and adapted to engage with a strand of the governor rope, together with means for actuating said auxiliary brake electro-magnetically, and means connected with said auxiliary brake for opening the motor power circuit, substantially in the manner and for the purpose set forth. 35

2. In combination with an elevator of the character designated, an auxiliary brake positioned on the car and adapted to engage with a strand of the governor rope, means for actuating said auxiliary brake electro-magnetically, means connected with said auxiliary brake for opening the motor power circuit, and independent electrical means for closing said motor power circuit, substantially in the manner and for the purpose set forth. 40 45 50

ABRAHAM STOLLER.
